LEGGING

Donald E. Kimball, Cleveland, Ohio

Application April 14, 1938, Serial No. 201,964

4 Claims. (Cl. 36—2)

This invention relates to quickly detachable leggings, more particularly intended for use in foundries and the like, to protect workmen from flying sparks and particles of molten metal, and has for an object new and improved leggings of this character.

In the drawing accompanying this specification and forming a part of this application, I have shown, for purposes of illustration, embodiments which my invention may assume, and in 10 the drawing:

Figure 1 is a side elevational view of an embodiment of the invention.

Figure 2 is a front elevational view of said embodiment, showing the legging in open spread 15 out position.

Figure 3 is an enlarged fragmentary, part sectional, part elevational view, with portions broken out to more clearly disclose underlying construction,

Figure 4 is a side elevational, part sectional, fragmentary view of said embodiment, disclosing fastening means for the upper portion of the legging, while

Figure 5 is a view similar to Figure 3, and 25 showing a different embodiment of the invention.

As shown in the drawing, the body portion of the legging is indicated generally by the reference character 10, and comprises a single piece of material, such as leather, cut out at its lower central portion, as indicated at 11. Fitted into the cut-out 11 is an instep portion 12, which projects forwardly, and is adapted to cover the instep of the user, being secured in position in the cut-out by stitching 13.

The overlapping end 14 of the legging is turned upon and stitched to itself, in such manner as to form an elongated pocket 15, preferably tapering from top to bottom, and adapted to accommodate stiffening means 16, the lower end of the pocket terminating short of the bottom edge of the legging, as at 17. The stiffening means 16 comprises a somewhat resilient rod or wire, bent into a pair of rod sections or legs 18 and 19, joined at the lower ends by a bent connecting section 20, the stiffening means 16 being accommodated within, and projecting a suitable distance below the terminal end 17, of the pocket 15. The upper free extremities of the rod sections or legs 18 and 19 are spaced apart, and curled to form eyelets 21 and 22, through which extend rivets 23, these rivets extending entirely through the outer wall of the pocket 15, and through the adjacent portion of the body 10 of

the legging, thus anchoring the stiffening means 16 in position. The sections 18 and 19 of the stiffening means 16, are additionally anchored by rivets 24, the shanks of which are accommodated by loops or eyelets 25, formed by bending each of the rod sections 18 and 19 into inwardly extending, oppositely disposed, substantially circular looped formations, which lie in the plane of the remainder of the stiffening means 16, without overlapping of the parts of the rod sections which form the loops, the small gaps 26 of the latter preferably being disposed outwardly, the rivets 24 of course extending through the wall of the pocket 15 and body portion of the legging, and being headed outwardly, as indicated at 27. By forming the eyelets or loops 25 in the manner described double thickness of the wire or rod sections is avoided. Pocket means 28 are provided at the opposite lower underlying end 29 of the legging for accommodating the projecting part 30 of the stiffening means 16, these pocket means comprising a strip of material secured in position by spaced sets of rivets arranged to define a pair of spaced pockets or loops 31, either one of which will snugly accommodate the projecting part 30 of the stiffening means 16, when the legging has been wrapped around the leg of the wearer.

The upper portion of the overlapping end 14 of the legging has fastened thereto, preferably by stitching 32, an elongated piece of material, preferably leather, which projects laterally outwardly beyond the edge of the overlapping end 14, to form a projecting flexible tab or flap 33, and preferably secured somewhat inwardly of the outer end of the tab 33 are hook-like fastening means 34, preferably including a piece of resilient rod or wire, bent in the form of a hook, including a body portion 35, an intermediate portion 36, and an inclined end portion 37, the wire as thus bent including spaced leg sections 38 and 39, the free ends of which are curled, to provide eyelets 40 through which extend the shanks of rivets 41, the rivets extending entirely through the tab 33 and headed on their outer ends, as will be understood. The leg sections 38 and 39 are also provided with substantially circular loops or eyelets 42, similar to the loops or eyelets 25—25 already described, and each of these loops 42 accommodates the shank of a rivet 43, these rivets extending entirely through the tab 33 and upset, or headed, at the outside. The leg section 38 is bent, as at 44, to provide a recess, the entrance to which is somewhat restricted, for a purpose which will presently appear.

The opposite, or underlying end 29, of the legging, adjacent the upper portion thereof, and at a level to dispose the upper edge substantially in line with the lower edge of the strip or tab 33, has another strip of material 45 secured thereto, preferably secured by rivets 46, the upper rivets being spaced apart predetermined distances to provide a plurality of keepers 47 with which the hook-like fastening means 34 may be selectively engaged.

In Figure 5, stiffening means 48 are provided, which are generally similar to the stiffening means 16 already described. In this construction, however, instead of loops 25—25 being employed to anchor the stiffening means, the wire is bent in a complete circle to form closed eyelets 49, through which extend the shanks of securing rivets 50 in the manner already explained. The projecting means 51 of the stiffening means 48, is formed at its end with an enlarged or flared section 52, which when engaged in one of the pockets 31 tends to prevent accidental detachment of the projecting means 51 from the pocket.

In use, the legging thus provided, is readily attachable-detachable, and when applied, is wrapped around the leg of the user to dispose both ends of the legging at the outside, with the end 14 overlying the end 29, and the projecting part 30 (or 51) of the stiffening means 16 (or 48) engaged with one or the other of the pockets 31, as desired, while the flap 33 is manipulated so as to engage the hook-like fastening means 34 with one or the other of the keepers 47, and thus a quick snug fit of the legging is obtained, the recessed part 44 receiving the related keeper 47 in such a way that the hook-like fastening means 34 is assured against accidental detachment, remaining attached even though the user kneels, or accidentally strikes the lower end of the legging against some obstruction, normally tending to force the stiffening means in an upward direction, such upward movement because of the peculiar configuration of the hook-like fastening means causing the same to move somewhat in a clockwise direction, as viewed in Figure 4, and thereby tending to more securely fasten, rather than to disconnect the same. The legging, however, may be readily removed, merely by grasping the flap or tab 33, and pulling the same upwardly, thereby imparting a somewhat counter-clockwise movement to the hook-like mechanism 44, causing the same to be cammed from engagement with its related keeper 47, and this same movement retracts the projecting part 30 (or 51) from the pocket 31 in which it was placed, thus disconnecting the entire fastening means. The formation of the stiffening means 16 (or 48) and the hook-like fastening means 34, from somewhat resilient rod or wire, not only renders the entire legging more flexible and comfortable to

the wearer, but reduces the area of the parts which normally become overheated, and greatly reduces the weight of the legging as compared to those of ordinary or usual construction.

5 It will be apparent to those skilled in the art that I have accomplished at least the principal object of my invention, and it also will be apparent to those skilled in the art that the embodiments herein described may be variously 10 changed and modified, without departing from the spirit of the invention, and that the invention is capable of uses and has advantages not herein specifically described, especially in connection with various kinds of clothing, and the like; hence it will be appreciated that the herein disclosed embodiments are illustrative only, and that my invention is not limited thereto.

I claim:

1. A legging of the overlapping type having 20 stiffening means secured along one end, and comprising an elongated rod reversely bent to form spaced sections, the free ends of which are formed with eyelets for the reception of securing rivets, and the opposite ends of which are joined to form a bight portion; and means carried by the opposite end of said legging with which said bight portion is adapted to be engaged.

2. A legging of the overlapping type having 30 stiffening means secured along one end of said legging, and comprising an elongated rod bent to shape and having a projecting portion, said rod intermediate its ends having bent portions forming eyelets for the reception of securing means; and means carried by the opposite end 35 of said legging with which said projecting portion is adapted to be engaged.

3. A legging of the overlapping type having 40 stiffening means secured along one end of said legging, and comprising an elongated rod bent to shape and having a projecting portion, said rod intermediate its ends having an offset substantially closed formed loop for the reception of 45 securing means; and means carried by the opposite end of said legging with which said projecting portion is adapted to be engaged.

4. A legging of the overlapping type, comprising: keeper means secured to the upper part of the underlying portion, and hook-like fastening means carried by the upper part of the overlying portion, said hook-like means including rod means having spaced sections bent into hook-like form and adapted to be detachably engaged with said keeper means; stiffening means extending along the overlying portion of said legging and including elongated rod means bent to shape and having a projecting portion; and pocket means upon said underlying portion for the reception of said projecting means.
